FOOT CONTROL FOR DENTAL HANDPIECES

Milton R. Nielsen, Wheaton, and Richard W. Lanigan,
Arlington Heights, Ill., assignors to Midwest Dental
Mfg. Company, Melrose Park, Ill., a corporation of
Illinois

Filed July 22, 1964, Ser. No. 80,963

Term of patent 14 years

(Cl. D24—1)

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a perspective view of a foot control for dental handpieces showing our new design;

FIG. 2 is a top plan view;

FIG. 3 is a side elevational view;

FIG. 4 is a front elevational view;

FIG. 5 is an elevational view of the side opposite the one shown in FIG. 3;

FIG. 6 is a rear elevational view;

FIG. 7 is a perspective view of an alternate form of the design;

FIG. 8 is a top plan view of the alternate design;

FIG. 9 is a side elevational view of the alternate design;

FIG. 10 is a front elevational view of the alternate design;

FIG. 11 is an elevational view of the alternate design taken from the side opposite the one shown in FIG. 9; and

FIG. 12 is a rear elevational view of the alternate design.

The fragmentary broken lines are shown for illustrative purposes only.

We claim:

The ornamental design for a foot control for dental handpieces, substantially as shown and described.
